POURING LIP FOR FLUID CONTAINERS

Charles S. Packer, Chicago, Ill., assignor to Just-
rite Manufacturing Company, Chicago, Ill., a
corporation of Illinois

Application March 3, 1941, Serial No. 381,434

1 Claim. (CL 221—6)

The invention relates to containers for liquids and has more particular reference to a gasoline container of the portable type having improved cover means for the pouring spout thereof and a novel pouring lip in combination with said spout.

The principal object of the invention is to provide a safety container for volatile liquids whereby the liquids can be transported or stored with the minimum of danger, which will have a special cover for closing the pouring spout and for sealing the same unless positively opened, and which will also embody a novel pouring lip in combination with said spout.

In containers of the present type it is necessary to provide a pouring spout that can be capped in a manner to completely seal the contents of the container from the atmosphere. This is required in order to eliminate all danger of fire or explosion. A cylindrical shape for the pouring spout has been found to present the least difficulties as regards manufacture and this shape of spout is the least expensive to make. In addition to the cylindrical shape of the spout the top surface of the same is circular and flat throughout its extent since structure of this nature makes possible the convenient closing and sealing of the spout by a circular cover having a resilient pad of rubber, neoprene or other similar material for coaction with the top. If this were not the case gasoline cans and the like would have spouts similar to those found in water pitchers and coffee pots since the pouring of a liquid from such spouts is materially facilitated and the liquid can be poured without spilling.

In view of the above considerations, containers for storing and transporting volatile liquids have been provided with a cylindrical spout having a circular top opening substantially flat throughout its extent in order to make possible the convenient closing of the container and sealing of the contents from the atmosphere. However, it is practically impossible to pour liquid from such spouts under any and all conditions without at times having some of the liquid run down the sides of the spout and the sides of the container to form a pool on the floor. This is, of course, dangerous since the liquid is volatile and a fire or explosion may result.

The improved pouring lip of the invention overcomes the above difficulties by facilitating the pouring of the liquid from a spout of circular shape having a substantially flat top, and wherein the improved pouring lip also effectively prevents

the liquid from running down the sides of the container during the pouring operation.

Another object of the invention resides in the provision of an improved pouring lip which may be located on the spout so as not to interfere with the action of the cover in closing the spout to seal the contents of the container.

Another object of the invention is to provide a pouring lip which will be relatively inexpensive to manufacture and which will have an improved mode of operation in facilitating dispensing of the liquid.

With these and various other objects in view, the invention may consist of certain novel features of construction and operation as will be more fully described and particularly pointed out in the specification, drawing and claim appended hereto.

In the drawing which illustrates an embodiment of the device and wherein like reference characters are used to designate like parts—

Figure 1 is a fragmentary elevational view showing the top portion of a container including a pouring spout with a cover therefor and which spout embodies the improved pouring lip of the invention;

Figure 2 is a sectional view taken substantially along line 2—2 of Figure 1 but which shows the pouring lip in top plan;

Figure 3 is a view taken substantially along line 3—3 of Figure 1 showing the resilient pad for the pivoted cover; and

Figure 4 is a fragmentary elevational view illustrating the improved operation of the pouring lip during the pouring of the liquid from the container.

Referring to the drawing, the can or container 10 is of conventional construction, having a pouring spout 11 and a reinforcing top plate 12. The pouring spout is cylindrical in shape, having substantially straight side walls and being suitably secured by means of the base portion 13 to the top of the container 10. More particularly the spout is located on the left side of the center line 40 passing vertically through the container. The spout provides an opening 19 leading to the interior of the container and by means of which the contents thereof may be dispensed. For convenience in dispensing the liquid within the container the spout is positioned on the top portion 45 at a slight inclination with respect to a horizontal plane.

The spout 11 is provided with a cover indicated in its entirety by 14 and which cover has a hinge portion 16 pivotally connecting, by means of a

stud or pivot shaft 17, with bifurcated ears 18 extending rearwardly from the spout. As a result of the hinged connection of the cover to the spout the cover may oscillate from a closed position to an open position. This latter position is shown in Figure 1. When the cover is closed on the spout it will be understood that the contents of the container are sealed from the atmosphere. The stud 17 for hinging the cover is best shown in Figure 2, wherein it will be observed that said stud passes through both of the ears 18 and through the hinge portion 16 of the cover. On the respective sides of said hinge portion and having encircling relation with the stud are coil springs 20. The coil springs are provided for yieldingly forcing the cover into a closed position on the spout. Each coil spring has a portion 21 which continues upwardly and passes around the center member 22 on the cover 14. The members 21 in effect join the respective coil springs 20 and as shown in Figure 1, said coil springs at their other end have portions 23 which extend downwardly to contact the spout 11.

It is necessary to close containers of the present type when not in use since such containers generally contain volatile liquids such as gasoline and the like. The cover must not only yieldingly return to a closed position when released by the actuating member 24 but said cover must have adhesion with the flat top surface 25 of the spout so as to seal the contents of the container from the atmosphere. This closing and sealing of the container by the cover is made possible through a pad 26 of resilient material, Figure 3, such as rubber, Neoprene, cork or the like. As shown, the pad has location within the cover 14 on the underside thereof. A recess is formed on this side of the cover by means of the depending flanges 27 and said recess is especially provided for receiving the pad. A central screw 28 or other similar securing means may be employed for holding the resilient pad to the cover. When the cover is closed the pad will have contact with the flat top surface 25 of the pouring spout. As a result of the pressure applied to the cover by means of the resilient coil spring 20 the said resilient pad will effectively seal the interior of the container from the atmosphere.

In containers of the type herein referred to it is necessary to provide a pouring spout that can be capped in a manner to completely seal the contents to prevent fire or explosion. Accordingly, the pouring spouts for such containers are cylindrical in form and the top surface is flat throughout its extent. A pouring spout of this shape makes it possible to conveniently close and seal the spout by a circular cover having a resilient pad as described. Although the spout may have a form other than circular, which would require that the cap conform thereto, such non-circular shapes for pouring spouts involve complications in their production and their manufacturing costs are considerably higher.

Although the above considerations make it desirable to use circular pouring spouts, such spouts present difficulties in the pouring of the liquid. Ordinarily it is impossible to pour from such a spout under any and all conditions without at times having some of the liquid run down the sides of the container to form a pool on the floor. I have found that the above difficulties can be effectively overcome by providing such pouring

spouts with a pouring lip indicated by numeral 30, Figure 1. Said pouring lip is located on the spout 11 at some distance below the flat top surface 25 so that the lip will not interfere with the cover 14 when said cover is in closed position on the spout. Also it will be observed that the pouring lip may be cast integral with the spout and accordingly manufacturing costs are not materially increased. Although the lip may be cast integral, it is also possible to form the same as a separate unit and weld the lip to the cylindrical spout.

As shown in Figure 2, the pouring lip 30 gradually increases in width toward the spout and the sides merge gradually into the cylindrical walls of the spout. Also in accordance with the invention the top surface, indicated by numeral 31, of the pouring lip 30 is formed so as to provide a slight inclination in a direction downwardly and outwardly from the spout 11. This inclination aids the flow of the liquid from the spout as said flow is in a downward direction to coincide therewith. However, whereas, the top surface 31 is inclined downwardly, the bottom surface 32 forms an exterior angle with the straight side walls of the spout which is approximately a ninety degree angle. In order to insure proper operation of the pouring lip during pouring of the liquid from the container the undersurface of the lip should not extend in a downward direction as this would aid the flow of the liquid down the side of the container. This feature of the pouring lip can best be understood by reference to Figure 4, which is a fragmentary elevational view illustrating the improved operation of the lip during the pouring of the liquid from the container. Since it is necessary to tilt the container during pouring, the undersurface 32 of the lip 30 therefore has a very definite inclination in an upward substantially vertical direction. The liquid is thus prevented from flowing along the undersurface 32 and accordingly the liquid leaves the lip and the flow down the sides of the container is prevented.

The invention is not to be limited to or by details of construction of the particular embodiment thereof illustrated by the drawing, as various other forms of the device will of course be apparent to those skilled in the art without departing from the spirit of the invention or the scope of the claim.

What is claimed is:

In a container of the character described, in combination, a pouring spout of cylindrical shape, said spout having circular inner and outer walls and a flat top surface between said walls, a pivoted cover for the spout, resilient means yieldingly maintaining the cover in closed position on the spout in contact with the flat top surface thereof, a pouring lip for said spout comprising a projection extending laterally from the outer wall of the same and having location below the flat top surface thereof so as not to interfere with the cover when in closed position, and said pouring lip having an undersurface which forms with the outer wall of the spout an exterior angle of approximately 90 degrees, whereby said undersurface of the pouring lip slopes substantially vertically when the container is in pouring position.

CHARLES S. PACKER.
